UNITED STATES PATENT OFFICE.

HENRY W. POOL, OF PROVIDENCE, RHODE ISLAND.

MUSIC-LEAF TURNER.

SPECIFICATION forming part of Letters Patent No. 338,103, dated March 16, 1886.

Application filed June 10, 1885. Serial No. 168,207. (No model.)

To all whom it may concern:

Be it known that I, HENRY W. POOL, of the city and county of Providence, and State of Rhode Island, have invented a new and useful Improvement in Music-Leaf Turners, of which the following is a full, clear, and exact description, reference being had to the accompanying drawings, forming a part of this specification.

- 10 My invention relates to attachments for pianos, organs, and music-stands, &c., by means of which the music-leaves may be turned in accordance with the performer's progress through the composition; and the object of 15 my invention is to produce a music-leafturner which may be quickly and readily manipulated without affecting the execution of the piece.

To the above purpose my invention consists in certain peculiar and novel features of construction, whereby the leaves are turned over and back again, according to the requirements of the composition, as hereinafter described and claimed.

- 20 In order that my invention may be fully understood, I will proceed to describe it with reference to the accompanying drawings, in which—

Figure 1 is a perspective view of my improved music-leaf turner. Fig. 2 is a sectional view of the same on the line 2 2 of Fig. 1. Fig. 3 is a similar view of the same on the line 3 3 of Fig. 1. Fig. 4 is a detached view of the carrier and its immediate connections. 35 Fig. 5 is a perspective view of a modified form of my invention.

In the said drawings, A designates the framework of the device, a a' the end pieces thereof, and a² a³ brackets extending from frame A.

- 40 B designates a roll, which is journaled at its ends in the end pieces, a a', and upon which is formed a spiral groove, b. Just back of this bar B, and extending parallel therewith, is a rod, C, the ends of which are also set in the end pieces.

D designates a bar, which rests at its ends in the end pieces, a a', but which is set obliquely to the roll B and bar C, said bar D being nearer to bar C at the end piece, a, and 45 farther from bar C at end piece, a'.

Upon the bar D are mounted two sliding

blocks, E E', having each a clamping-screw, e, and a rack-bar, e', the latter extending toward each other and lapping at their outer ends.

55 E² designates a gear-pinion, which is interposed between the two rack-bars e' e', and with the teeth of which it engages, so that when one block is moved toward or away from the center of the frame upon bar D the other block will be similarly moved.

F designates a carrier, which is mounted upon roll B, and which is formed with projections f, engaging in grooves b of said roll. The roll B is also provided with a gear-pinion, b', which is located in the center of the roll. A bracket, a⁴, extends downward and outward from frame A, and this bracket is formed with two arms, a⁵ a⁶. Upon the arm a⁵ is pivoted a toothed segment, G, the teeth 65 of which engage with those of the pinion b'. Upon the arm a⁶ is pivoted at h a lever, H, the inner end of which is pivoted to the lower end of a link, h', the upper end of which is pivoted at h² to the segment G. Thus it will 70 be seen that when the outer end of lever H is depressed the segment G will be raised and the roll B will be revolved. As the roll revolves the carrier F, working in groove b, will be thrown to the left. When the lever 75 H is released, the weight of the segment will cause it to fall, and the roll B will be revolved in the opposite direction, and consequently the carrier F will be thrown back to the right again.

85 I' I² I³ designate three travelers, mounted to slide freely upon bar D, and having an arm, i i' i³, respectively. The outer ends of these arms engage successively at the beginning of the movement of carrier F to the right beneath a latch, f', pivoted upon carrier F. A wire, f², extends upward through carrier F, and is adapted to rise and fall therein, and the upper end of said wire is so bent as to engage beneath said latch, so that when the wire 90 is raised it will raise the latch with it.

J designates a lever, which is also pivoted at h upon arm a⁶, opposite to arm H. The inner end of this lever is pivoted to the lower end of a link, j, the upper end of which is in 95 turn pivoted to the outer end of a rod, j'. This rod is bent at one end so as to extend out to 100

its connection with link j , and extends horizontally to the end piece a , at which point it is pivoted to the end piece, a . Thus it will be seen that when the lever J is depressed the rod j' will be raised, and, engaging the wire f^2 , will raise it, and with it the latch f' . Each of the traveler-blocks, $I^1 I^2 I^3$ carries also a rod, $i^4 i^5 i^6$ respectively, each of which is arranged to slide in its respective block, and each of which is formed with a knob or head, i^7 , upon its rear end.

K designates a guide-rod, which is secured to the end piece, a , and the outer end of which is so bent as to engage in front of the knobs $i^4 i^5 i^6$ on rods $i^4 i^5 i^6$ and to draw said rods backward away from carrier F , as said travelers are thrown to the right. At the opposite end of the frame are mounted three rods, $L L' L^2$, the outer ends of which are set in slots in the end piece, a' , springs l being employed to hold the ends of the rods against the forward ends of the slots. The opposite ends of these rods are pivoted, respectively, to pull-rods $M M'$, which extend out beyond the front of the frame and carry heads or buttons $m m'$. The rods $L L' L^2$ are also formed with bends $l' l^2 l^3$, as shown. The travelers $I^1 I^2 I^3$ carry each a grooved ball, $i^8 i^9 i^{10}$, in the grooves of which are fastened wire clips $i^{11} i^{12} i^{13}$.

N designates an arm, which is pivoted at n to the frame, and the lower bifurcated end, n' , of which rests against cams g , formed upon segment G , the arrangement being such that when the segment is raised the bar N will be thrown outward by the cams, and thus permit the leaf to be turned.

The operation of the device is as follows: The sheets of the music are grasped by the clips $i^{11} i^{12} i^{13}$, said clips being set to the right-hand side of the frame, and the stops E being adjusted to accord with the width of the open sheet. As soon as the first page of music has been played the performer depresses lever H , and thus throws carrier F toward the left-hand end of the frame, the arm N moving forward to allow the sheet to turn. The travelers are not acted on by the carrier throughout the entire length of their movement in this direction, owing to the divergence of bar D from bar C and roll B , which draws the arm of the traveler away from the latch of the carrier, but sufficient momentum is acquired by the traveler to enable it to finish its movement. The carrier returns again to its original position when the lever H is released, and its latch catches the arm of the next traveler, while the arm N falls back again upon the music-sheet. These operations are repeated until the whole number of sheets are turned. In case there are no returns in the composition this completes the action of the device; but supposing that at the end of the last bar there is a return to a bar on the first page, stop l is pulled out, and as the first traveler reaches the bend in the

corresponding rod L the rod i^4 is thrown forward so that when the carrier is thrown to the left the outer end of rod i^4 slips over the face of the carrier and is thrown outward by spring l , so as to engage against the right-hand side of the carrier. When the carrier returns again, it carries all of the travelers with it to the right-hand end of the frame. The same operation occurs if the return be to the second or third sheet, and as the travelers arrive at the right-hand end of the frame their rods are drawn back by the rod K . Now, supposing that after having played the return on the first sheet, it is desired to turn to the third the lever J is depressed so as to raise latch f' , and thus allow said latch to pass over the arms of the first two travelers. The latch then engages with the arm of the third traveler, and when lever H is thrown toward the left it carries the first and second travelers with it.

It is evident that the number of travelers, rods $L L' L^2$, &c., and stops $m m'$ may be more or less than three, according to circumstances. The knobs or rods $i^4 i^5 i^6$ are relatively longer in the order named, so that each knob shall be acted upon only by its particular rod $L L'$, &c.

In Fig. 5 the gear-pinion b' is placed at the right-hand end of the roll B , while the segment G is pivoted upon a bracket, a^7 , extending downward from end piece, a . The levers $H J$ are pivoted upon a bracket, a^8 , extending downward and forward from frame A , a thumb-screw, a^9 , being used to pivot the levers. In other respects the arrangement is the same as before, excepting that arm N is dispensed with.

Having thus described my invention, I claim as new and desire to secure by Letters Patent—

1. In a music-leaf turner, a revolving grooved roll and a carrier operated thereby, in combination with one or more leaf-turners thrown by said carrier, and mechanism, substantially as described, for operating said roll, as set forth.

2. The combination, with a revolving grooved roll, and a carrier operated thereby and provided with a latch, of one or more leaf-turners or travelers having each an arm engaging with said latch, and a bar for guiding the movements of the travelers and set obliquely to the roll, substantially as described.

3. The combination, with a grooved revolving roll, a carrier operated thereby and provided with a latch, of one or more travelers moving upon a bar set obliquely to the roll, and provided each with an arm to engage the latch, and fixed and movable guide-rods for extending and retracting the traveler-rods to engage with and clear the carrier, substantially as specified.

4. The combination of frame $A a a'$, grooved roll B , bars $C D$, levers $H I$, rods $j' L L'$, &c., pull-rods $M M'$, &c., carrier F , with its latch

f' , and travelers I I', &c., with their arms and sliding rods having the knobs, as described.

5. The combination, with frame A a a', grooved roll B, bars C D, rods K L L', &c., stops E, with rack-bars e', pinion E', carrier F, with its latch f', and wire f², of travelers I I', &c., with their clips, arms, and sliding rods,

and the levers H I, segment G, with cam g, pinion b', arm N, pull-rods M M', &c., and rod j', as set forth.

HENRY W. POOL.
